(57) **CLAIM**

The ornamental design for a protective case, as shown and described.

DESCRIPTION

FIG. 1 is a perspective view of a first embodiment of the protective case of the present invention;
 FIG. 2 is a front elevational view of the case of FIG. 1;
 FIG. 3 is a left side elevational view of the case of FIG. 1, the right side being a mirror image thereof;
 FIG. 4 is a rear elevational view of the case of FIG. 1;
 FIG. 5 is a top plan view of the case of FIG. 1;
 FIG. 6 is a bottom plan view of the case of FIG. 1;
 FIG. 7 is a perspective view of a second embodiment of the protective case of the present invention;
 FIG. 8 is a front elevational view of the case of FIG. 7;
 FIG. 9 is a left side elevational view of the case of FIG. 7, the right side being a mirror image thereof;
 FIG. 10 is a rear elevational view of the case of FIG. 7;
 FIG. 11 is a top plan view of the case of FIG. 7; and,
 FIG. 12 is a bottom plan view of the case of FIG. 7.
 The broken line showing of environment in the drawings is for illustrative purposes only and forms no part of the claimed design.
